KITCHEN RANGE

Bond C. White, Bellefonte, Pa.

Application December 26, 1941, Serial No. 424,509

1 Claim. (Cl. 126—1)

This invention relates to new and useful improvements in ranges, and more particularly to a range which can be installed in low cost homes, apartments and other places lacking basements for storage purposes, this with a view toward having provided in such a dwelling a small store room for the storage of fuel, et cetera, and building in the range of the present invention so that the major portion thereof will project into said storage room, while the front service portion thereof will be exposed through a wall of the usual kitchen.

Therefore, the principal object of the present invention is to provide a kitchen range which will take up no space in the usual small kitchen of a low cost home or apartment due to the fact that its service portion or front is accessible through an accommodating opening in one wall of the kitchen.

Other objects and advantages of the invention will become apparent to the reader of the following description.

In the drawings:

Figure 1 is a fragmentary front elevational view showing the range through an opening in a kitchen wall.

Figure 2 is a vertical sectional view showing the range in side elevation.

Figure 3 is a sectional view taken substantially on line 3—3 of Figure 2.

Figure 4 is a sectional view taken substantially on line 4—4 of Figure 1.

Referring to the drawings wherein like numerals designate like parts, it can be seen that Figure 2 which is a vertical section through a wall 5 shows that this wall 5 is formed with an opening 6 therein to accommodate the range 7, that is, the range 7 is situated in a storage room 8 and has its front or service side projecting into the opening 6 and terminating flush with the kitchen side of the wall 5, numeral 9 denoting the kitchen.

The range in construction comprises side walls 10, 11, a back wall 12 and a front made up of a stationary panel 13, a hinged panel 14 and an oven door 15, the panel 14 and door 15 having handles 16 and 17, respectively.

The panel 14 is in front of a warming oven 18 (see Fig. 3) which is covered by a removable plate 19. Additional removable plates 20, 21 and 22 form the stove top and have removable lids 23 thereon.

Porcelain walls 24 rise above the side walls 10,

11 of the stove and a back wall 25 of porcelain rises from the back wall 12, it being understood, of course, that any well finished wall structure can be used in place of the walls 24, 24, 25. These last-mentioned walls are preferably backed by slabs or sheets of insulation 26. Suitable studing 27 are employed in the mounting of the walls and slabs last referred to.

Numeral 28 denotes a metallic canopy having 10 an outlet 29 at its top, this for the purpose of carrying off fumes from the area above the range.

At the side wall 10 is a fuel door 30 preferably having a damper therein, while at the back wall 12, that is, behind the fire box 31 and above the 15 grate 32, is another fuel door 33. An ash door 34 is located in the back wall 12 below the grate 32.

An elbow 35 extends from the upper portion 20 of the hot air compartment 36, at the back wall 12, and numeral 37 denotes a stack rising from this elbow 35.

It can here be seen that in order to fire or clean out ashes from the range, the storage room 8 must be entered, as wood, coal or other fuel is to be kept in this room. Thus, it can be 25 seen that the range is readily accessible to a person in the kitchen 9, but will create no undesirable condition in the kitchen as would certainly occur if firing, ash removing, et cetera was required on the kitchen side of the range.

30 While the foregoing specification sets forth the invention in specific terms, it is to be understood that numerous changes in the shape, size and materials may be resorted to without departing from the spirit and scope of the invention as 35 claimed.

Having described the invention, what is claimed as new is:

In combination, a range and a partition wall 40 having front and back sides and adapted to divide two rooms, said wall having an opening therein, said range having its front side extending through said opening in said wall and flush with said wall so that the front side of the range is accessible at the front of said wall while the 45 back part of the range extends rearwardly from the back side of said wall, side walls and a back wall rising from said range, and a fume removing canopy above and extending from the side and back walls to form therewith an enclosure open 50 at the front side and accessible through said opening.

BOND C. WHITE.
